UNITED STATES PATENT OFFICE.

WILLIAM A. TURBAYNE, OF NIAGARA FALLS, NEW YORK, ASSIGNOR TO U. S. LIGHT & HEAT CORPORATION, OF NIAGARA FALLS, NEW YORK, A CORPORATION OF NEW YORK.

RHEOSTAT AND OPERATING MEANS THEREFOR.

1,251,594.

Specification of Letters Patent.

Patented Jan. 1, 1918.

Application filed August 19, 1914. Serial No. 857,478.

To all whom it may concern:

Be it known that I, WILLIAM A. TURBAYNE, a citizen of the United States, residing at Niagara Falls, in the county of Niagara and State of New York, have invented new and useful Improvements in Rheostats and Operating Means Therefor, of which the following is a full, clear, concise, and exact description, reference being had to the accompanying drawing, forming a part of this specification.

This invention relates to improvements in rheostats and operating means therefor.

A rheostat is employed in many systems of automatic regulation in which it is desired that the rheostat shall remain inactive until certain predetermined circuit conditions obtain, when it is automatically brought into action. Such a system is extensively employed in connection with electric car lighting on railway cars. In railway lighting systems, an axle-driven generator furnishes current to light the lamps and charge a storage battery. The battery supplies the lamps when the generator is operating at low speed or is at rest. The generator is regulated by means of variable resistances in the field circuit of the generator. It is desirable to bring these resistances into operation upon certain definite circuit conditions obtaining in the system. Thus, current-controlled resistances are brought into operation at definite current values to limit the output of the generator or the charging current for the battery. Also, voltage-controlled resistances are brought into operation at definite voltages across the system to regulate the battery charge or other electrical conditions. Various conditions of service demand various arrangements, but the underlying principle is common that at some definite current or voltage value the regulator must be brought into operation.

An object of the present invention is to provide a variable resistance having operating means for bringing the resistance into operation under conditions which may be accurately predetermined.

Another object is to provide a variable resistance having a single operating coil for bringing the resistance into operation and thereafter controlling the variation thereof.

Another object is to provide a variable resistance and operating means which are not

thrown out of adjustment by the rough usage incident to car lighting service.

Another object is to provide a compressible rheostat having a single operating coil for bringing the rheostat into operation at a predetermined current strength through the coil and which will thereafter be operated by the coil responsive to a different value of current through the coil, to vary the resistance.

The above and other objects may be attained by the embodiment of the invention illustrated in the accompanying drawings. The views in the drawings are as follows:

Figure 1 is a front elevation of the rheostat.

Fig. 2 is a top plan thereof.

Fig. 3 is a vertical section on the line A—A of Fig. 1.

Fig. 4 is a vertical section on the line B—B of Fig. 3.

In a co-pending application, Serial No. 762,053, filed April 18, 1913, Patent No. 1,131,176, issued March 9, 1915, certain of the broad features of the invention are described and claimed.

In the embodiment of the invention herein illustrated, the variable resistance is in the form of a compressible rheostat, although it is obvious that other forms of rheostat may be employed. The resistance elements of the rheostat comprise a plurality of contacting electrodes 10 of carbon or other suitable material, preferably in the form of disks. The carbon disks are arranged between a relatively fixed abutment 11 and a movable abutment 12. The electrical resistance of the rheostat is varied by varying the pressure on the series of disks. When the pressure is increased, the electrical resistance decreases, and when the pressure is relaxed, the electrical resistance increases.

The operating means for varying the pressure includes an electro-magnetic winding 13 on the parallel legs 14 of a horse-shoe magnet. The magnet has an upper pivoted armature 15, adapted to be attracted to the upper poles of the magnet, and a lower pivoted armature 16 adapted to be attracted to the lower poles. A magnet frame 17 supports the carbon disks 10 and the windings. A bracket 18 on the frame provides a pivotal attachment for the armature 15, and a bracket 19 provides a pivotal attachment for

the armature 16. The armature 15 is normally held in retracted position away from the magnet by a spring 20 attached to the arm 21, extending from the armature 15, beyond its pivot. The spring is adjustable by an adjusting bolt 22 to which one end of the spring is attached. Adjustment of the bolt is secured by a nut 23 threaded on the bolt and bearing against the frame 17. The armature 15 is pivotally attached to a rod 24 which carries the movable abutment 12 for the carbon disks. The armature 15 is provided with a laminated portion 25 of good magnetic material, adjacent the upper pole faces of the magnet. The upper pole faces are cut away diagonally at 26 and the laminated portion of the armature has its ends beveled so as to provide a long range of attraction and also to give an increasing attraction as the armature moves downward. This increasing attraction compensates for the increasing counter-pressure on the carbon disks as they are compressed. Movement of the armature away from the magnet is limited by an adjusting screw 27 carried in a bracket 28 supported on the magnet frame.

The lower armature 16 is normally retracted by gravity, although it may also be provided with a retracting spring, if desired. Its movement away from the magnet is limited by an adjusting screw 29 carried in bracket 30 supported from the magnet frame. The armature carries a bridging member 31 of material of low magnetic reluctance. This member is adapted to bridge the lower pole pieces when the armature is attracted and provide a path of low magnetic reluctance for the flux of the magnet, for a purpose hereinafter described. The lower armature is designed to act as a relay to control external circuits or the circuit through the resistance elements, and to this end carries a resilient contact 32. This contact is adapted to make contact with adjustable upper and lower contacts 33 and 34 which are provided with proper external leads.

A common dash-pot steadies the action of both armatures and prevents the jars and vibrations of service from affecting the armatures. The upper armature is pivotally connected to the cylinder 35 of the dash-pot and the lower armature is pivotally connected to the piston 36.

The rheostat operates as follows: The normal upper air gap between the armature and poles is made so great that the armature is not attracted by energization of the windings so long as the lower air gap is open. By this causing the upper armature to remain fixed, the reluctance of the magnetic circuit is maintained constant so that the lower armature may be accurately adjusted by means of the screw 29 to close at a definite energization of the coil. As soon as the lower armature is attracted the member 31

bridges the lower pole pieces and so reduces the reluctance of the magnetic circuit that the upper armature is immediately brought under the influence of the windings and will be caused to exert a varying pressure on the carbon disks in proportion to the energization of the windings.

The device may be readily set to respond to different current values in the windings by varying the normal positions of the armatures by means of the adjustable stops.

It is possible to set the lower armature to respond to a definite voltage across the coil or a definite current value through the same, which, as already explained, would be insufficient to operate the rheostat, as long as the lower air gap is open. As soon as the lower armature is raised and the lower air gap eliminated, the upper armature is within the radius of influence of the magnet and may be set to operate in response to a definite value of voltage across the coil or current therethrough. Thus, in a unitary device, it is possible to employ a single normally energized coil which will prevent operation of the regulator until certain definite circuit conditions obtain, after which point the regulator will automatically operate to maintain proper conditions in the system, which conditions may be different from those which initially caused the regulator to respond.

The improved arrangement of a single dash-pot controlling both armatures prevents jars to which the regulator may be subjected from prematurely closing the air-gap and causing operation of the regulator before proper conditions have been reached.

It is to be understood that the embodiments of the invention herein described are merely for the purpose of illustration, as it is apparent that many modifications in details of construction and arrangement of parts may be made without sacrificing the advantages of the invention as set forth in the appended claims:

1. Regulating means including a compressible rheostat, a movable member for compressing said rheostat, an electro-magnetic winding provided with parallel cores having oppositely beveled ends, a wedge shaped armature carried by said movable member and adapted to cooperate with the beveled ends of said cores, said armature being normally outside the radius of influence of said winding, and means under control of said winding to bring said armature within the influence of said winding.

2. Regulating means including a compressible rheostat and electro-magnetic means for compressing said rheostat, said electro-magnetic means being provided with means for increasing the effectiveness thereof to compensate for increasing resistance to compression as said rheostat is operated, said electro-magnetic means including an oper-

ating member normally ineffective to vary the rheostat, and a member responsive to a predetermined energization of the electro-magnetic means for rendering the operating member effective.

3. Regulating means including a rheostat, a member for operating said rheostat, a pair of windings arranged on parallel cores, an armature adapted to bridge the air gap between adjacent ends of said cores and an armature controlling said rheostat operating member normally outside the radius of influence of said winding but automatically brought into said influence by the decrease in reluctance, as said first armature is operated to close the air gap.

4. Regulating means for an electric circuit including a rheostat, means for varying the resistance of said rheostat, an electro-magnetic winding normally ineffective to operate said means and means operated by said winding for increasing the radius of influence of said winding to bring said rheostat operating means within the influence of said winding.

5. In a regulator, an electro-magnetic winding, a pair of armatures, separately movable thereby, and a dash pot for steady-ing the operation of said armatures, one of said armatures being connected to the piston of said dash pot and the other armature being connected to the cylinder of the dash pot.

6. A compressible rheostat including a resistance element adapted to be compressed and an electro-magnetic winding for controlling the compression of said element, said winding having an armature normally uninfluenced by current through said winding, said armature being mechanically connected to the resistance element to compress the same, said winding also having a second armature adapted to be attracted by said winding and to reduce the reluctance of the magnetic circuit of said winding and thereby to cause the first armature to be operated by said winding.

7. A compressible rheostat including a resistance element adapted to be compressed, an electro-magnetic winding for controlling the compression of said element, said winding having an armature normally uninfluenced by current through said winding, said armature being mechanically connected to the resistance element to compress the same, said winding also having a second ar-

mature adapted to be attracted by said winding to reduce the reluctance of the magnetic circuit of said winding and thereby to cause the first armature to be operated by said winding, and a single dash pot for steady-ing the operation of both of said armatures.

8. A compressible rheostat including a resistance element adapted to be compressed, an electro-magnetic winding for controlling the compression of said element, said winding having an armature normally uninfluenced by current through said winding, said armature being mechanically connected to the resistance element to compress the same, said winding also having a second armature adapted to be attracted by said winding to reduce the reluctance of the magnetic circuit of said winding and thereby to cause the first armature to be operated by said winding, and a single dash pot for steady-ing the operation of both of said armatures, one of said armatures being mechanically connected to the movable piston of said dash pot and the other armature being connected to the movable cylinder within which said piston operates.

9. A compressible rheostat including a resistance element adapted to be compressed, an electro-magnetic winding for controlling the compression of said element, said winding having an armature normally uninfluenced by current through said winding, said armature being mechanically connected to the resistance element to compress the same, said winding also having a second armature adapted to be attracted by said winding to reduce the reluctance of the magnetic circuit of said winding and thereby to cause the first armature to be operated by said winding, and a single dash pot for steady-ing the operation of both of said armatures, one of said armatures being mechanically connected to the movable piston of said dash pot and the other armature being connected to the movable cylinder within which said piston operates, said second armature having means for adjusting the point at which it may be operated by said winding.

In witness whereof, I have hereunto subscribed my name in the presence of two witnesses.

WILLIAM A. TURBAYNE.
